UNITED STATES PATENT OFFICE.

HENRY R. VAN EPS, OF PEORIA, ILLINOIS.

DESIGN FOR A GATE.

SPECIFICATION forming part of Design No. 21,502, dated April 26, 1892.

Application filed February 13, 1892. Serial No. 421,488. Term of patent 3½ years.

To all whom it may concern:

Be it known that I, HENRY R. VAN EPS, a citizen of the United States, residing at Peoria, in the county of Peoria and State of Illinois, have invented certain new and useful Improvements in Design for Gates; and I do hereby declare that the following is a full, clear, and exact description of the invention, which will enable others skilled in the art to which it appertains to make and use the same.

This design is intended for gates, and the essential features thereof are shown in the gate as the same is illustrated in the accompanying drawing, which represents a front view of the same.

Referring now to said drawing by letters, the main structure is formed by the perpendicular side pieces *a a*, the top piece *a'* bearing at right angles with the side pieces for a short distance and obliquely upward meeting at the central point or perpendicular line through the center of the gate and the horizontal cross-pieces *c c c*.

b b are ornaments secured by any suitable means at the points indicated in the drawing.

e e are scrolls bearing between the top piece

a' and the upper cross-piece *c* and secured to the respective pieces at points of contact by any suitable means.

f is a name-plate bearing between and upon the inner ends of the scroll.

g g g g are large scrolls bearing against and secured to the side pieces *a a* at their outer extremities and against the cross-pieces, to which they are secured at top and bottom and against each other, as indicated in the drawing, and the conjunction of two scrolls *g g*, giving the heart form.

d d d, &c., are depending rods or bars in arrangement and form as indicated in the drawing, the parts and arrangements thereof constituting the ornamental design to be employed in the gate.

What I claim as new is—

The design for a gate, as herein shown and described.

In testimony whereof I affix my signature in presence of two witnesses.

H. R. VAN EPS.
